CLAIM

The ornamental design for filter cartridge, as shown and described.

DESCRIPTION

FIG. 1 is a perspective view of a filter cartridge according to the present design; in FIG. 1 the perspective view being shown generally toward a seal end, and toward a media pack side.

FIG. 2 is a perspective view of the filter cartridge of FIG. 1 taken toward an opposite end to FIG. 1.

FIG. 3 is a first side elevational view of the filter cartridge of FIG. 1; the view of FIG. 3 generally being toward the side viewable in FIG. 1.

FIG. 4 is second side elevational of the filter cartridge of FIG. 1; the view of FIG. 4 being taken generally toward an opposite side to that viewable in FIG. 3.

FIG. 5 is a first end elevational view of the filter cartridge of FIG. 1.

FIG. 6 is a second end elevational view of the filter cartridge of FIG. 1; the view of FIG. 6 being opposite the view of FIG. 5.

FIG. 7 is a flow end plan view of the filter cartridge of FIG. 1; the end viewable being that viewable in FIG. 1; and, FIG. 8 is opposite flow end plan view of the filter cartridge of FIG. 1; the view of FIG. 8 being taken generally opposite the view of FIG. 7.

The broken-lines in the drawings show portions of the filter cartridge that forms no part of the claim.

The filter cartridge is shown with a symbolic break in its length. The appearance of any portion of the article between the dash-dot-dash break lines forms no part of the claimed design.
